UNITED STATES PATENT OFFICE.

FRANK W. PARKHURST, OF FARMINGTON, NEW HAMPSHIRE, ASSIGNOR OF ONE-HALF TO WALTER AMAZEEN, OF FARMINGTON, NEW HAMPSHIRE.

SNOWPLOW.

Application filed November 20, 1925. Serial No. 70,301.

- The object of this invention is to provide a snow plow which includes a motor vehicle, preferably of the tractor type, and a snow-removing structure carried by and projecting forwardly from the vehicle and adapted to deflect snow upwardly and rearwardly from a horizontal surface, and thereby form a track of uniform width, and to shift the deflected snow to one side of the track.
- 10 The invention is embodied in the improvements hereinafter described and claimed.
- Of the accompanying drawings forming a part of this specification.—
- Figure 1 is a side elevation of a snow plow embodying the invention.
- 15 Figure 2 is a front end view.
- Figure 3 is a section on line 3—3 of Figure 1.
- Figure 4 is a section on line 4—4 of Figure 2.
- 20 Figure 5 is a top plan view, showing the forward portion of the plow.
- Figure 6 is a section on line 6—6 of Figure 5, and a side elevation of the parts at the left of said line including means for driving the blower rotor and the conveyer hereinafter described, at different speeds.
- 25 Figure 7 is a section on line 7—7 of Figure 6.
- Figure 8 is a view similar to Figure 2, showing the snow-removing structure hereinafter described, embodied in a single unit, instead of in the two units shown by Figure 2.
- 30 Figures 9, 10 and 11 are views showing the hereinafter described blower rotor.
- The same reference characters indicate the same parts in all of the figures.
- In the drawings, *a* designates the body of
- 35 *a* motor vehicle, which may be of any suitable type, and is provided with running gear including motor driven tractors at opposite sides of the vehicle and traction wheels forward of the tractors. One of
- 40 the tractors and one of the traction wheels is shown by Figure 1, these being designated respectively by *b* and *c*. *d* designates the hood covering the motor, not shown.
- 45 Projecting forward from the motor vehicle and carried thereby, is a snow-removing structure adapted to upwardly and rearwardly deflect snow in advance of the vehicle in such manner as to form a track of
- uniform width, said structure being as next described.
- 50 In the preferred embodiment of the invention, shown by Figures 1 to 7, inclusive, the snow-removing structure includes two tapering conduits located side by side, tapering helical conveyers carried by shafts rotatable in the conduits, two blower casings, located behind the conduits, each provided with a blower rotor, the conveyers being adapted to force snow through the conduits and into the blower casings, and the rotors being adapted to force the snow from the blower casings through an outlet common to the casings. The structure therefore includes two snow-removing units, each of which may be described as follows:
- 55 12 designates a tapering conduit having a larger forward end portion, the lower side of which has a substantially horizontal collecting edge 13, the conduit being adapted to deflect snow upward and rearward from the collecting edge. The conduit has a smaller delivering rear end 14, which is substantially circular in cross section, and is adapted to discharge the deflected snow at the rear end of the conduit.
- 60 15 designates a blower casing, adapted to receive snow from the delivering end 14, and provided with a snow outlet 16.
- 65 17 designates a substantially horizontal longitudinally extending conveyer shaft supported by bearings 18 and 19, forming parts of the structure. The shaft extends through the conduit and blower casing and is centrally arranged therein, as indicated by Figures 2 and 4. 20 designates a tapering helical conveyer fixed to the shaft within the conduit 12, and adapted to feed the deflected snow into the blower casing 15. The larger end of the conveyer is at the forward end of the shaft 17 and is substantially flush with the receiving end of the conduit. The smaller end of the conveyer 20 is adjacent to the delivering end of the conduit. The taper of the conduit conforms to that of the conveyer as shown by Figure 4, and the arrangement is such that snow collected by the edge 13 is guided by the conduit toward the axis of the conveyer, is condensed by the conduit, and is positively forced by the conveyer from the receiving to the delivering end of the conduit.

Supported by the shaft 17, within the blower casing is a blower rotor, designated as a whole by 21, adapted to discharge snow through the outlet 16, the rotor being coaxial with the conveyer.

The rotor may be fixed to the shaft 17 and rotated in unison with the conveyer. If desired, however, the rotor may be driven at a faster rate than the conveyer, as described 10 hereinafter, with reference to Figures 6 and 7.

The shaft 17 is driven by the engine, through suitable connecting mechanism. Said mechanism, in this instance, includes a 15 transverse conveyer and rotor-driving shaft 22, journaled in bearings on the removing structure and provided with a bevel gear 23, and with a pulley 24, connected as by a belt 25, with a suitable element of the motor. 20 The pulley may be provided with sprocket teeth, and the belt may be a sprocket chain. The bevel gear 23 meshes with a bevel gear 26, fixed to the shaft 17.

The blower casing outlet 16, which in the 25 two-unit construction shown, communicates with two blower casings, as shown by Figure 3, is provided with a swivelled elbow-shaped terminal 30, adapted to be swung horizontally to various positions to deliver snow in 30 any desired direction. The terminal is provided with a pulley 31, on which runs a flexible connection or cable 32, the ends of which are so engaged with a drum 33 carried by the vehicle, that a rotation of the drum causes 35 a turning movement of the terminal 30. The drum is located in position to be rotated by the driver whose seat is shown at *a*. The snow-removing structure is vertically adjustable, so that the collecting edge 13 may 40 be raised to an inoperative position, permitting progress of the plow without removing snow, and different heights of the collecting edge when snow is being removed. To this end the structure includes rearwardly projecting arms 34, bolted to the blower casing and hinged at 35 to the vehicle body. Said arms are provided between their ends with bearing faces 34^a which, as shown by Figures 1 and 4, are the upper sides of slots 45 formed in the arms. Journaled in bearings on the body is a transverse adjusting shaft 36, having eccentrics 37. The bearing faces 34^a of the arms rest on said eccentrics, so 50 that the arms and the snow-removing structure are variably supported by the vehicle body through the shaft 36 and the eccentrics, the latter being under compressive pressure by the weight of the structure. The shaft 36 is provided with a worm gear 38 (Figure 5), meshing with a worm 39, on an operating rod or shaft 40, which is journaled in bearings on the body and provided with a handle 41, within reach of the driver. Rotation of the rod 40 causes the rotation of the 55 eccentrics and an upward or downward

swinging movement of the arms and the entire snow-removing structure. It will be seen that the eccentrics remain in any position to which they may be turned and do not require locking means.

The collecting edge 13 constituting the lower portion of the receiving end or mouth of the conduit 12, is longer than the greatest diameter of the helical conveyer 20, and is adapted to take up a thin and relatively wide layer of snow which moves upward and rearward on the lower portion of the conduit, the snow being forced inward toward the axis of the conveyer by the tapering conduit, and at the same time compressed, so that practically all portions of the snow entering the conduit are within the control of the conveyer and are positively forced thereby through the outlet 14 into the blower casing.

As shown by Figure 2, I prefer to make the receiving mouth of the conduit 12 square or rectangular, although it is obvious that its upper portion may be curved or arched, to conform to the upper portion of the conveyer.

In the preferred two-unit construction, the collecting edges 13 of the conduits 12 are in line with each other, as shown by Figure 2, and collectively form a relatively wide track, the driving shaft 22 is elongated and provided with two bevel gears 23, as shown by Figure 5, and the snow outlet 16 communicates with the two blower casings 15, as shown by Figure 3.

It is obvious that the snow-removing structure may be composed of a unit including one of the conduits 12 and one of the conveyers 20, as shown by Figure 8, the snow outlet 16 communicating with only one blower casing. In this embodiment of the invention the driving shaft 22 is provided with only one bevel gear 23.

As previously stated, the blower rotor may be driven from the motor through independent torque-transmitting means, so that the rotor and the conveyer 20 may be driven at different speeds. This result may be accomplished by the means shown by Figures 6 and 7, and next described.

The blower rotor is fixed to a hub or sleeve 42, loosely rotatable on the shaft 17 to which the helical conveyer is fixed. To the sleeve 42 is fixed a relatively small spur gear 43. To the bevel gear 26, which is fixed to the shaft 17, is fixed a larger spur gear 44. Fixed to the blower casing 15 is a stud 45, on which are mounted to rotate loosely, two rigidly connected spur gears 46 and 47 of different diameters. The smaller gear 46 meshes with the gear 44 fixed to the bevel gear 26. The larger gear 47 meshes with the gear 43 fixed to the sleeve or hub 42 of the blower rotor. Torque is transmitted from the bevel gear 26, and the spur gear 44 fixed thereto, to the

connected gears 46 and 47, and by the gear 47 to the gear 43. The relative proportions of said gears are such that the blower rotor is driven at a higher speed than the helical 5 conveyer.

The preferred construction of the blower rotor, designated as a whole by 21, is shown by Figures 9, 10 and 11. The rotor as here shown includes two circular heads 10 50 and 51, fixed to and spaced apart by the hub or sleeve 42 and flat rectangular blades 53, riveted to and extending between the heads. The head 50 at the forward side of the rotor is interrupted by central openings 15 54 (Figure 10) formed between radial spoke portions 55 of the head and collectively forming a snow-receiving inlet registering with the outlet end 14 of the tapering conduit 12. The head 51 is closed or continuous 20 from its margin to the sleeve 42, as shown by Figure 11, so that it arrests or deflects snow forced into said inlet. The blades 53 are radially arranged and their inner ends are at the margins of the openings 54, as 25 shown by Figure 10. The spoke portions 55 may have sharp cutting edges enabling them to pass freely through compressed snow passing from the tapering conduit to the blower casing. The described construction 30 ensures a maximum capacity of the blower for a given diameter.

It will be seen that the forced feed helical conveyer 20 takes snow from the large area bounded by the receiving end of the tapering 35 conduit 12, the snow being collected by the relatively long collecting edge 13 in a relatively thin sheet or layer, and conveyed through the constantly diminishing diameter of the conduit into the center of the blower casing, from which it is thrown outward through the outlet or exhaust pipe 16.

The helical conveyer may be made with one or more convolutions, and it extends forward so that its larger end is substantially 40 flush with the receiving end of the conduit. The forward or cutting edge of the conveyer is practically as long as the width of the receiving end of the conduit between opposite edges thereof, sufficient clearance being provided to prevent chafing. The circular inner end portion of the tapering conduit 12 includes the major portion of the length of the conduit, the squared outer end portion 45 extending inwardly from the receiving forward end sufficiently to form a four-sided receiving end, one of the sides of which includes the collecting edge 13. This form facilitates making a clean path through deep snow, and enables two conduits to be readily 50 connected and permit a maximum width of snow removal without obstruction to the view of the operator.

The collecting edge 13 is preferably provided with a reinforcing strip 13^a to increase 55 its durability.

It is obvious that runners may be substituted for the traction wheels c.

I claim:

1. A snow-plow comprising a motor vehicle, and a snow-removing structure carried by and projecting forward from the vehicle and including a longitudinally extending conveyer shaft driven by the engine of the vehicle and provided with a tapering helical conveyer, the larger end of which is at the 70 forward end of the shaft; a tapering conduit conforming to the taper of the conveyer, said conduit having a larger receiving forward end substantially flush with the larger end of the conveyer, and a smaller delivering rear end adjacent to the smaller end of the conveyer, the lower side of the receiving end being formed by a horizontal snow-collecting edge, the arrangement being such that snow collected by said edge is guided by 75 the tapering conduit toward the axis of the conveyer and thereby condensed, and is positively forced by the conveyer from the receiving to the delivering end of the conduit. 80

2. A snow-plow as specified by claim 1, the snow-removing structure including also rearwardly projecting arms hinged at their rear ends to the vehicle body to swing vertically, and provided with bearing faces; and mechanism carried by the vehicle body for 85 swinging said arms to vertically adjust said structure, said mechanism comprising a transverse adjusting shaft supported by the body and provided with eccentrics on which said bearing faces rest, so that said structure is supported by the body through the 90 adjusting shaft and eccentrics, and means operable by the driver to turn the adjusting shaft and its eccentrics and thereby vertically adjust the structure, the eccentrics being adapted to remain in any position to 95 which they may be turned. 100

3. A snow-plow as specified by claim 1, the snow-removing structure including also rearwardly projecting arms hinged at their 105 rear ends to the vehicle body to swing vertically, and provided with bearing faces; and mechanism carried by the vehicle body for swinging said arms to vertically adjust said structure, said mechanism comprising a 110 transverse adjusting shaft supported by the body and provided with eccentrics on which said bearing faces rest, so that said structure is supported by the body through the adjusting shaft and eccentrics, the adjusting 115 shaft being provided with a worm gear, and a manually operable operating shaft supported by the vehicle body and provided with a worm meshing with said gear to turn the adjusting shaft and its eccentrics, and thereby vertically adjust the structure. 120

4. A snow-plow as specified by claim 1, the snow-removing structure including also a blower casing through which the conveyer 125 shaft extends, said casing communicating 130

with the outlet end of the tapering conduit and having a snow outlet, and a blower rotor mounted on the conveyer shaft within the casing and driven by the engine of the vehicle to force snow from the blower casing through the outlet.

5. A snow-plow as specified by claim 1, the snow-removing structure including also a blower casing communicating with the delivering end of the tapering conduit, and provided with a snow outlet having a swivelled terminal, and a blower rotor in said casing coaxial with the helical conveyer and driven by the engine to force snow through the outlet; and mechanism carried by the vehicle body and operable by the driver for swinging said terminal to variably direct the discharged snow.

6. A snow-plow as specified by claim 1, the snow-removing structure including also a blower casing communicating with the delivering end of the tapering conduit, and provided with a snow outlet having a swivelled terminal and a blower rotor in said casing coaxial with the helical conveyer and driven by the engine to force snow through the outlet; and mechanism carried by the vehicle body and operable by the driver for swinging said terminal to variably direct the discharged snow, said mechanism including a manually rotatable drum adjacent to the driver's seat and a flexible cable connecting said drum with a pulley on the swivelled terminal.

35 7. A snow-plow as specified by claim 1,

the snow-removing structure including also a blower casing communicating with the delivering end of the tapering conduit, and provided with a snow outlet, a blower rotor mounted on the conveyer shaft within the casing to rotate independently of the shaft, and torque-transmitting means connecting the conveyer shaft with the rotor and organized to drive the rotor at a higher speed than the conveyer.

8. A snow-plow as specified by claim 1, the snow-removing structure including also a blower casing communicating with the delivering end of the tapering conduit and provided with a snow outlet, and a blower rotor in said casing coaxial with the helical conveyer and driven by the engine to force snow through the outlet, said rotor including two rigidly connected spaced apart heads, one having openings collectively forming a snow inlet coinciding with the outlet end of the tapering conduit and adapted to receive snow therefrom, said head having snow-cutting spoke portions between the openings, the other head being closed to arrest snow entering the openings, and radial blades fixed to and extending between said heads, the inner ends of the blades being at the outer margin of the snow inlet, so that snow arrested by the closed head is engaged by the blades and forced outwardly thereby to the snow outlet.

In testimony whereof I have affixed my signature.

FRANK W. PARKHURST.
